CHILD'S SWING

Oscar A. Watts, French Settlement, La.

Application January 6, 1943, Serial No. 471,461

2 Claims. (Cl. 155—58)

This invention relates to a structurally novel and functionally improved child's swing for use indoors or out-of-doors, and especially suitable for use on one's porch, the same having particular reference to a single portable chair-like construction adapted to be swingably hung from the porch ceiling or equivalent support by appropriate suspension chains or the like.

Resembling as it does the bench-type, slatted form, multiple occupant porch swing; the construction forming the preferred embodiment of the invention is a diminished or miniature likeness to the regular bench swing. Built on this smaller scale, and adapted for rough handling and usage, it is possessed of unique structural features which serve to render it aptly fitted for such purposes. With these two requisites in mind, and in reducing the invention to practice, I have devised a swing expressly adapted for use by children, the same being characterized by strength and durability, weather worthiness, practical usefulness, and being of such design and configuration as to tend to minimize injury to the small occupants.

Visualized in a general manner, the preferred construction embodies a substantial slatted base or bottom and an upstanding slatted back rest, together with appropriately fashioned members forming arm rests. In reference to this general arrangement, a specific object of the invention is the construction of the base section, this embodying a practical frame structure made up of suitably designed and interconnected frame members specifically arranged as hereinafter described.

Of outstanding importance as an object of the invention is the back rest, this being characterized by a carefully selected arrangement of members for bracing and reinforcing purposes and an upper portion characterized by adjoining front and back slats forming a cap-like safety shield, or protector.

The third feature has to do with the parts constituting the arm rests, said parts including horizontal rails and vertical struts, said rails being intimately associated with the brace assembly embodied in the aforementioned back rest structure.

Other features and advantages of the invention will become more readily apparent from the following description and drawings.

In the accompanying drawings, wherein like numerals are employed to designate like parts throughout the views:

Figure 1 is a side elevational view of the com- 55 of the suspension chain rods or bolts 13 extend

plete child's swing constructed expressly in accordance with the principles of the present invention.

Figure 2 is a top plan view of the structure seen in Figure 1 with the suspension chains omitted for clearness of illustration.

Figure 3 is a rear elevational view depicting to advantage the back rest and especially the criss-cross bracing.

Figure 4 is a bottom plan view of the seat section or unit.

Figure 5 is an enlarged fragmentary detail sectional view taken on the plane of the line 5—5 of Figure 1 looking in the direction of the arrows and detailing the association of parts forming the frame in the seat or bottom section.

Figure 6 is an enlarged vertical fragmentary section taken on the plane of the line 6—6 of Figure 3 looking in the direction of the arrows.

Figure 7 is a horizontal fragmentary enlarged detail section on the line 7—7 of Figure 2 showing the lower corner construction of the basal or seat part of the structure.

Figure 8 is an exaggerated perspective view showing the interconnection of members or elements forming essential parts of the preferred types of arm rests.

Figure 9 is a horizontal section on the plane of the line 9—9 of Figure 1 employed to bring out how the horizontal rails of the arm rests join up with the back rest and bracing means for distribution of stress and strain.

Scanning the illustrative drawings, it will be observed that the swing, as a whole, is made up of three main components; namely, the seat or so-called slatted bottom, the especially designed and braced slatted-type back rest, and, finally, the two duplicate arm rests.

The specific construction of the seat unit is evident from Figures 1, 4, 5 and 7. Referring, first, to Figure 4, it will be observed that the frame is expressly designed for rigidity and durability. The horizontal frame members 10 are parallel to each other and also to a central brace 11, the latter having notches adjacent its ends to accommodate the intermediate portions of the complementary frame members 12 arranged at right angles to the first-named frame members 10 and 11. The intermediate portions fitting into the notches in the part 11 are flush with the lower edge of said part 11, as brought out in Figure 5. The end portions of the members 12 have overlapping connection with the frame members 10 and at the points of intersection the lower ends

of the suspension chain rods or bolts 13 extend

therethrough. This provides for ideal anchorage of the eyebolts or stays 13 and also properly assembles the five-slat frame elements 10, 11 and 12. The narrow front and rear slats 14 and 15 serve to finish out the adjacent areas smoothly and also function as convenient drop or apron elements. The main wider slats 16 are suitably mounted on the frame. Thus, we have a five-element or part frame with its parts carefully designed and coacting to ably accommodate the slats or finishing elements.

The seat structure is referred to by the letter S to distinguish it, as a unit, from the back rest unit B. Now, in reviewing critically the construction of the part B, we observe that it is essentially made up of uprights 17 having horizontal back resting slats 18 appropriately attached thereto. Particular attention is called to the cap-like shield or guard at the top made up of the companion slats 19 and 20, these converging by securing the slat 19 to the mitered upper ends of the uprights 17. This provides an ideal protective guard in case the child stands up in the swing. This is, therefore, the aforementioned essential safety feature, or, at least, may be singled out as such. It is to be observed in Figure 4 that the lower ends of the uprights are carefully joined up with the frame elements 10 and 12 and are directly bolted, as at 21, to the adjacent frame elements 12. In addition, I call attention to the X-shaped bracing means comprising a single long brace 22 and two co-acting shorter braces 23 interposed between the uprights 17. Further, at the approximate point where the parts 22 and 23 abut one another there is a reinforcing cross piece 24, this bridging the coacting portions of said braces 22 and 23 as brought out to advantage in Figure 3. There is also a centrally positioned vertical reinforcing brace 25, this having its upper feather edge connected with the slat 20 and its lower end underneath said cross-piece 24 and seated in the crotch formed by the abutting portions of the parts 22 and 23. Altogether these components 17, 22, 23, 24 and 25 contribute their proportionate share in making up a carefully balanced and reinforced frame structure in the back rest unit. Here, again, I provide for uniform distribution of strain and stress and this emphasizes the aforementioned feature of rigidity and stability so necessary in a child's swing. In fact, children's playthings in this category are subject to rough handling and usage, and hence it is important to build the parts to withstand such activity.

I call attention now to the arm rests, each of which comprises a horizontal hand rail or part 26. This part has its rear end notched out, as at 27, to engage the post or upright 17, where it is fastened in place by a bolt or the like 28. The notched portion 27 extends beyond the post where it nestles in abutting relation with the end of the reinforcing cross piece 24. The upper end of the vertical strut, that is, the extension 29 of the strut 30 (see Fig. 8) fits into a notch in the outer end of the rail 26. The parts are bolted together at 31 for security in assemblage and association. Carrying out further the idea of careful selection and coordination of parts, it will be observed that the lower ends of the struts 30 actually project down into the seat arrangement, as shown in Figure 7. What is more, the overlapping of the ends 10 and 12 at this point provides an ideal association permitting the lower end of said strut to be bolted at 32 to the projecting terminal or end of the frame part 10. The upper

ends of the eyebolts pass through the hand rail 26 and, if desired, metal clips 33 (see Fig. 1) serve to contribute additional stability.

In reviewing the drawings and description, I desire to emphasize the novel features; namely, the five-part frame arrangement shown in Figure 4 with the overlapping ends of the parts 10 and 12 serving for ingenious nesting of the struts 30 and uprights 17 in place. Or in other words, these parts 30 and 17 are thus securely anchored in the seat and the fastenings are underneath the seat so as to occupy a safe spot. The frame structure itself made up of the parts 10, 11 and 12 is believed to be novel. Particularly do I emphasize the criss-cross and bracing structure shown in Figure 3, this forming the essence of the back rest. Furthermore, attention is called to the upper mitered ends of the uprights 17 whereby to permit the parts or slats 19 and 20 to come together in forming a topping cap or shield for the upper portion of the back rest. It follows, therefore, that Figure 9 illustrates one feature of the construction and Figure 7 another feature. Thus, all of the views together give a clear impression of what are thought to be outstanding structural arrangements in a child's swing construction.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details coming within the field of invention claimed may be resorted to in actual practice, if desired.

I claim:

1. In a chair-type porch swing expressly built for children, a substantially rectangular seat unit including a frame, said frame comprising a pair of opposed parallel frame elements disposed in an even plane with one another, a second pair of frame elements disposed in a plane with each other but on a plane below the first-named elements, the second-named elements being disposed and positioned inwardly of the outer ends of the first-named elements and crossing and overlying said first-named elements and being bolted thereto, a back rest including a pair of spaced parallel uprights having their lower ends simultaneously contacting and bolted to the rear ends of the first-named frame elements and the end portions of one of the adjacent second-named frame elements, a pair of frontal vertical struts opposed to said uprights and having their lower ends resting in contact with the adjacent end portions of the first-named elements and the end portions of the adjacent one of said second-named frame elements and respectively fastened thereto, slats secured to the top surfaces of the frame elements of the first-named pair, slats secured across the back rest uprights, and a pair of arm resting rails horizontally disposed and connected to the intermediate portions of the uprights at their rear ends and secured to the upper ends of the struts at their outer forward ends.

2. In a chair-type porch swing expressly built for children, a substantially rectangular seat unit including a frame, said frame comprising a pair of opposed parallel frame elements disposed in an even plane with one another, a second pair of frame elements disposed in a plane with each other but on a plane below the first-named ele-

ments, the second-named elements being disposed and positioned inwardly of the outer ends of the first-named elements and crossing and overlying said first-named elements and being bolted thereto, a back rest including a pair of spaced parallel uprights having their lower ends simultaneously contacting and bolted to the rear ends of the first-named frame elements and the end portions of one of the adjacent second-named frame elements, a pair of frontal vertical struts opposed to said uprights and having their lower ends resting in contact with the adjacent end portions of the first-named elements and the end portions of the adjacent one of said second-

5 named frame elements and fastened respectively thereto, slats secured to the top surfaces of the frame elements of the first-named pair, slats secured across the back rest uprights, a pair of arm resting rails horizontally disposed and connected to the intermediate portions of the uprights at their rear ends and secured to the upper ends of the struts at their outer forward ends, and elongated eye-bolts passing through the overlapping end portions of the respective pairs of frame elements and having their upper ends secured to the end portions of the adjacent arm resting rails.

OSCAR A. WATTS.
